UNITED STATES PATENT OFFICE.

CHRISTIAN F. RETZER AND CHARLES LEGARD, OF SUPERIOR, WISCONSIN.

BRAKE-BEAM HANGER.

1,426,506.

Specification of Letters Patent. Patented Aug. 22, 1922.

Application filed June 6, 1921. Serial No. 475,273.

To all whom it may concern:

Be it known that we, CHRISTIAN F. RETZER and CHARLES LEGARD, both citizens of the United States, residing at Superior, in the county of Douglas and State of Wisconsin, have invented certain new and useful Improvements in Brake-Beam Hangers, of which the following is a specification, reference being had therein to the accompanying drawing.

This invention relates to brake beam hangers and has special reference to such a device for use in connection with railroad cars wherein the brake beams are pivotally suspended by ordinary hangers and subject to accident by the dropping of one or both ends of the brake beam.

The principal object of the invention is to provide a more convenient auxiliary or emergency hanger for brake beams than heretofore known.

Another object is to provide one that may be conveniently employed in the repair or adjustment of the brake beam of a car.

Other objects and advantages of the peculiar construction will appear in the further description of the invention.

Referring to the accompanying drawing forming part of this application in which like reference characters indicate like parts:

Figure 1 is a perspective view of one of our improved hangers, and

Figure 2 is a side elevation of a portion of a car truck showing the relative position of the hanger thereto.

The hanger comprises a vertically disposed supporting member 1 made of flat bar iron, twisted intermediate of its ends as at 2, so that such twisted portion is positioned at right angles to the remaining portions at either end. The upper end of the supporting member is provided with a plurality of holes 3 by which it is attached to the bolster 4 of the car truck 5. The lower end of the member 1 is flattened and has an eye 6 formed therein into which the ram's horn end 7 of the beam encircling portion or stirrup of the hanger is removably engaged.

The stirrup portion of the hanger is substantially rectangular in form except that the upper portion 8 is inclined upwardly towards the twisted portion 2 of the member 1, where it is turned at right angles

horizontally and formed into a pin member 55 which is engageable, through a suitable hole in the twisted portion 2, therewith, and a cotter 10 is used for retaining said parts cooperatively united.

From the foregoing it is evident that we 60 have provided a separable hanger, the stirrup portion of which may be quickly removed entirely when occasion demands same, or may be simply disconnected at its upper end by removing the cotter 10, thereby allowing the stirrup portion to drop down pivotally and be suspended from the eye 6 in the member 1, if such is sufficient for the necessary accessibility to and about the brake beam, which latter is illustrated 70 at 11 in Figure 2, the beam shown in dotted lines, Figure 1, representing that of a common I-beam, and which, when in position normally depending from the bolster of the truck, forms an efficient and reliable emergency hanger.

Having thus described our invention, what we claim and desire to secure by Letters Patent, is:

1. The combination with a railroad car 80 brake beam having the usual pivotal support therefor, of an auxiliary safety support for said beam comprising a vertically disposed depending member rigidly supported upon the car, and a stirrup like member separably united at one end to the lower end of the vertically disposed member and surrounding the brake beam and also separably united at its uppermost end to the vertically disposed member. 90

2. An auxiliary safety support for a brake beam of the character described comprising a depending rigidly fixed member disposed adjacent one side of the brake beam and having an eye formed in the 95 lower end thereof, a stirrup like member surrounding the brake beam with a ram's horn or helical terminal at one end and engageable within said eye with the opposite end removably attached to the member, 100 substantially as and for the purpose described.

3. An auxiliary hanger of the character described for brake beams comprising a rigidly fixed depending member and a horizontally disposed stirrup member disengageable at its upper end with the fixed member for removing and applying the 105

brake beam, and normally pivotally engaged at its lower end to the lower extremity of the fixed member, and means whereby rotative and swinging adjustment of the stirrup will separate same from the fixed member.

In testimony whereof we hereunto affix

our signatures in the presence of two witnesses.

CHRISTIAN F. RETZER.
CHARLES LEGARD.
